US00D519484S

(12) **United States Design Patent** (10) **Patent No.:** **US D519,484 S**
Wolf et al. (45) **Date of Patent:** **** Apr. 25, 2006**

(54) **COMMUNICATION DEVICE**

(75) Inventors: **Monika R. Wolf**, Parkland, FL (US);
Martin E. Holman, IV, Boca Raton, FL (US); **Dave H. Karl**, Fort Lauderdale, FL (US); **Daniel Cruz Ferreira Motta Veiga**, Oeiras (PT)

(73) Assignee: **Motorola, Inc.**, Schaumburg, IL (US)

(**) Term: **14 Years**

(21) Appl. No.: **29/220,758**

(22) Filed: **Jan. 5, 2005**

(51) **LOC (8) Cl.** **14-03**

(52) **U.S. Cl.** **D14/138**

(58) **Field of Classification Search** D14/137, D14/138, 147-148, 247-248, 144, 341-347; 379/433.01-433.13, 434; D21/517; 455/575.3, 455/566, 575.1; 345/169; 348/376, 14.02

(57) **CLAIM**

The ornamental design for a communication device, as shown and described.

DESCRIPTION

FIG. 1 is a front isometric view of an ornamental design for a communication device showing our new design; FIG. 2 is a front orthographic view thereof; FIG. 3 is a rear orthographic view thereof; FIG. 4 is a right side orthographic view thereof; FIG. 5 is a left side orthographic view thereof; FIG. 6 is a top orthographic view thereof; and, FIG. 7 is a bottom orthographic view thereof. The broken lines shown in FIGS. 1-7 are included for the purpose of illustrating environmental elements only and form no part of the claimed design.
